CLAIM

The ornamental design for a wireless keyboard, as shown and described.

DESCRIPTION

FIG. 1 is a front perspective view of a wireless keyboard, showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a rear perspective view thereof;

FIG. 9 is an enlarged detail view of area 9 in FIG. 1; and,

FIG. 10 is an enlarged detail view of area 10 in FIG. 8.

The even-dash broken lines shown in the drawings illustrate portions of the wireless keyboard, which form no part of the claimed design.

The dash-dot-dot broken lines represent the limits of the detail views and form no part of the claimed design.
